MELVIN L. SEVERY, OF ARLINGTON HEIGHTS, MASSACHUSETTS, AND GEORGE B. SINCLAIR, OF GEORGETOWN, MAINE.

RHEOSTAT.

1,236,772.

Specification of Letters Patent. Patented Aug. 14, 1917.

Original application filed February 25, 1910, Serial No. 545,963. Divided and this application filed December 22, 1914. Serial No. 878,471.

To all whom it may concern:

Be it known that we, MELVIN L. SEVERY and GEORGE B. SINCLAIR, citizens of the United States, residing, respectively, at 5 Arlington Heights, in the county of Middlesex and State of Massachusetts, and at Georgetown, in the county of Sagadahoc and State of Maine, have invented certain new and useful Improvements in Rheostats, 10 of which the following is a specification.

The present application is a division of an application, Serial No. 545,963, filed in our joint names on the 25th day of February, 1910, which eventuated in Letters Patent No. 1,125,746, dated January 19, 1915. 15 It is designed to cover separately and in detail the rheostat or resistance device set forth in the parent application as a part of the complete structure. This divisional 20 application is filed pursuant to official requirement.

In the accompanying drawings:

Figure 1 is a cross section of our rheostat; Fig. 2 is a perspective view of one of the 25 elements of the rheostat;

Fig. 3 is a perspective view of a coupled pair of said elements, but with the wiring thereof not shown;

Fig. 4 is a perspective view of the rheostat 30 box and brush carrier with the intermediate section of the same broken away; and

Fig. 5 is an enlarged edge view of an element showing a lead therefrom.

Each of the rheostat elements consists of 35 a thin rectangular plate of insulating material 1, having wound thereon a multiplicity of turns of fine wire 2. This wire is preferably bare, but is wound so perfectly parallel as not to allow contact between any of 40 its several coils or turns. At one edge of the plate 1, several of the windings or coils, preferably five, are prolonged into extension loops 3 and twisted more or less at such edge (as in Fig. 5) in order to retain such 45 coils in place. These extension loops 3 are to serve as lead wires by which the current can be cut into the resistance wire 2 at different points, and so vary the length thereof in a circuit. A lead wire 4 being 50 joined to the wire 2 at the extreme left hand end, as shown in Figs. 1 and 2, the circuit between the right-hand loop 3 and said wire 4 will comprise all the turns of the wire 2, while the circuits between the intermediate loops 3 and said wire 4 will embrace 55

fewer turns, and consequently have less resistance therein.

After the plate 1 has been wound as above set forth, with the loops 3 and lead 4 projecting therefrom, a suitable insulating material preferably in liquid form, as shellac or other varnish, is laid over the wires 2, either by means of a brush, by dipping the plate and windings in the liquid, or otherwise insuring the insulation of the wire; 60 for we have found that in use without these precautions, the wire 2 becomes more or less elongated relative to the plate 1, either by expansion of the wire or shrinkage of the plate, and the turns get displaced and parts 65 of the resistance thereby cut out. Two of these elements are then fastened to opposite sides of two thin bars 5, as by screws or rivets 6, and to the projecting ends of said bars is secured a cross piece 7 the outer 70 edge of which is curved concentric with a point just beyond the opposite ends of the elements 1; and to this curved edge or face are fastened several contacts 9 equal in number to the sum of the loops 3 on the two 75 elements 1. In the lateral face of this cross piece are formed grooves 10 into which the lead wire 4 and loops 3 are laid, each of them being suitably secured, preferably by solder, to a contact 9; the lead 4 and loops 80 3 of one element lying in grooves 10 at one side of the cross piece, and the lead and loops of the other element lying in the 85 grooves at the opposite side.

In the top and bottom of the elongated 90 box 11 are numerous transverse grooves 12 into which the coupled elements can be slid, the thin bars 5 fitting said grooves, and a longitudinal strip 13 limiting the distance to which said coupled elements go, as shown 95 in Fig. 1. At the back of this box is rotatably supported a longitudinal shaft 14, as in Figs. 1 and 4, substantially concentric with the curved faces of the cross pieces 7; and upon the ends of said shaft are fixed the arms 100 15 carrying at their free ends a bar 16, preferably of angle-iron, to the outer face of which is secured an insulating strip 17, preferably wood, carrying the brushes 18 whose extremities sweep the said contacts 9 as said 105 shaft is rocked, there being one brush for each resistance unit. The brush-carrying members are moved by means of gravity and a tension spring 19 and link 20 extending to any suitable operating means, different 110

groups of wires being successively added to or removed from the line or circuit as the brush-carrying member is thus shifted.

- In the drawings we have shown the groups of coils varying in the number of turns or windings which they respectively include. This may or may not be followed in practice, according as the rheostat is to be applied to one or another specific use.
- 10 The unequal spacing here shown is particularly intended for electrical musical instruments, and is set out in detail in the parent application, but not being claimed in this divisional application need not be further referred to herein. It will be observed that each contact brush 18 sweeps its own set of contacts 9, and cuts into or out of circuit the windings or coils of its own resistance unit only. By introducing each resistance unit 15 into a circuit or branch circuit individual to itself, the rheostat is adapted to control simultaneously and through movement of a single actuating member, as many circuits or branch circuits as there are resistance units and contact brushes. So, too, individual resistance units can be added, withdrawn, or replaced by others of different winding, as circumstances may require. The primary 20 field of use of the rheostat here set forth is in connection with electrically-actuated musical instruments, to vary the attracting power of the electromagnets thereof, but it is obviously capable of use in numerous other relations.
- 25 35 Having thus described our invention, what we claim is:—
1. A rheostat comprising a box transversely grooved in its top and bottom members; a plurality of plates slidably carried 40 in said grooves, each plate having wound thereon a multiplicity of turns of wire suitably insulated from each other, each plate having connected therewith a plurality of contacts wired to different sections of its 45 turns, all said contacts being in the same curved surface; a member pivoted to move concentric with said surface; and brushes

carried by said member to sweep said contacts.

2. A rheostat comprising a box transversely grooved in its top and bottom members; removable resistance elements therefor consisting in each case of two thin bars fitting said grooves, two flat plates fastened at their edges to said bars, each plate having wound thereon a multiplicity of turns of wire, an externally curved member fixed to the ends of said bars, contacts affixed to the curved surface of said member, leads between said contacts and different sections 55 of said turns, and a movable member carrying brushes sweeping said contacts.

3. A rheostat element comprising two thin bars; two rectangular plates of insulating material fastened to said bars, the edges 60 of the latter projecting beyond the edges of the plates, each plate being wound with a multiplicity of non-contacting turns of wire; a cross piece terminally fastened to the ends of said bars and having transverse 70 grooves in its lateral faces; contact blocks affixed to its outer face; and leads attached to said contacts and passing through said grooves to different sections of said turns of wire.

4. A rheostat comprising a supporting member, a plurality of resistance units carried thereby each having contacts located in the same curved surface, a shaft supported by said member concentric with said surface, arms rigid with said shaft, a cross bar carried by said arms, and brushes carried by 80 said bar in touch with said contacts.

In testimony whereof we have signed our names to this specification in the presence of 85 two subscribing witnesses.
